Filed Mar. 26, 1963, Ser. No. 74,146

Term of patent 14 years

(Cl. D22—2)

FIG. 1

FIG. 2

FIG. 3

FIG. 1 is a front perspective view of a toy can opener showing my new design;

FIG. 2 is a side elevational view showing the crank in lowered position and the can release arm in closed position; and

FIG. 3 is a rear elevational view thereof.

The essential feature of my design resides in the face panel as shown in FIG. 1 in combination with the particular base all as shown.

I claim:

The ornamental design for a toy can opener, as shown and described.
